[57] **CLAIM**

The ornamental design for a fiber optic connector plug, as shown and described.

DESCRIPTION

FIG. 1 is a front perspective view of a fiber optic connector plug showing our new design;

FIG. 2 is a rear perspective view of a fiber optic connector plug showing our new design;

FIG. 3 is a front elevational view thereof;

FIG. 4 is a rear elevational view thereof;

FIG. 5 is a side elevational view, the opposite side is a mirror image;

FIG. 6 is a top plan view thereof; and,

FIG. 7 is a bottom elevational view thereof.

The broken lines are for illustrative purposes only and forms no part of the claimed design.
